T. J. KEHOE,
LATCH OPERATING DEVICE,
APPLICATION FILED JULY 24, 1916.

1,357,991.

Patented Nov. 9, 1920.

Thomas J. Kehoe Inventor

By *Geo. K. Kehoe* Attorney

UNITED STATES PATENT OFFICE.

THOMAS J. KEHOE, OF TOLEDO, OHIO, ASSIGNOR TO THE WILLYS-OVERLAND COMPANY, OF TOLEDO, OHIO, A CORPORATION OF OHIO.

LATCH-OPERATING DEVICE.

1,357,991.

Specification of Letters Patent.

Patented Nov. 9, 1920.

Application filed July 24, 1916. Serial No. 110,863.

To all whom it may concern:

Be it known that I, THOMAS J. KEHOE, a citizen of the United States of America, residing at Toledo, Lucas county, Ohio, have 5 invented new and useful Latch-Operating Devices, of which the following is a specification.

This invention relates to latch operating devices, and particularly to latch operating 10 devices especially designed and adapted for automobile doors. The principal object of my invention is to provide an improved latch operating device for automobile doors, which may be constructed at low cost, and 15 which may be very readily and quickly assembled in place in the automobile door, and in which extreme accuracy in assembling is not necessary.

Further objects, and objects relating to 20 details of manufacture and economies of construction, will definitely appear from the detailed description to follow.

I accomplish the objects of my invention by the devices and means described in the 25 following specification. My invention is clearly defined and pointed out in the appended claims.

A structure constituting a preferred embodiment of my invention is illustrated in 30 the accompanying drawing forming a part of this specification, in which:

Figure 1 is a perspective view of a fragment of a motor vehicle body embodying the invention;

35 Fig. 2 is a detail view on an enlarged scale of the latch operating device in coöperating relation with the latch;

Fig. 3 is a sectional view on the line III—III Fig. 2, looking in the direction of 40 the arrow;

Fig. 4 is a sectional view on the line IV—IV Fig. 2, looking in the direction of the arrow; and

Fig. 5 is a sectional view on the line V—V 45 looking in the direction of the arrow.

The motor vehicle body 1 is provided with the door 2 having mounted therein the latch 3 normally thrust outward by the spring 4. This latch 3 is mounted to reciprocate in the latch box 5. Pivoted to the latch box 5 is the rockable or movable latch operating member 6 engaging the shoulder 7 on the latch 3 to operate the latch against the resistance of the spring 4 in withdrawing

the latch, say from holding position when 55 the door 2 is closed. The member 6 is provided with an eye 7 disposed in angular relation to the extent of the member 6. This eye is engaged by the curved end of the rock arm 8 provided with screw-threaded engagement in the fulcrum or mounting pin 9 having the manually engageable means or handle 10 with the free end 11 curved into position closely approximating the inner lining or upholstery of the door 2 to preclude 60 catching of clothing therein.

The fulcrum bracket 12 is provided with screw holes 13 through which screws 14 may extend to anchor the bracket in the frame of the door 2. This sheet metal bracket 12 has 70 the arm 15 folded in parallel relation with a portion of the plate 12 of the bracket to provide aligned bearings for the fulcrum 9 between which may act the rock arm 8 away from the integral stop 16. Engaging the 75 folded bracket portion 15 is the torsion spring 17 having its other terminal engage the fulcrum member 9. This torsion spring 17 normally takes up lost motion between the members 8, 6 and the latch 3, the spring 80 17 being weaker and acting in opposition to the spring 4 and accordingly in a direction to assist in the upward swing of the free end of the handle 10 in serving to unlatch the latch 3 or move the latch 3 into withdrawn 85 position.

The loose connection between the members 6 and 8, due to this spring 17 as a vibration take-up, has snug coaction at all times and the mounting of the bracket 12 may be 90 varied through a considerable range without interfering with the operative assembly when the member 8 is in coacting position with the eye 7'. Accordingly, considerable rapidity of assembly may be had in 95 a device of simple construction, strong and positive in operation and effectively withdrawing the reciprocable member or latch.

What is claimed and it is desired to secure by United States Letters Patent is:

1. In a device of the class described, the combination of a sliding latch bolt, a spring normally pressing said bolt outwardly, a pivoted lever for retracting said latch bolt, a roll back operatively associated with said lever to move it against the action of said spring and a second spring acting upon the roll back in opposition to the first mentioned

spring to partially overcome the resistance thereof and to yieldingly press the operating arm of the roll back against said lever.

2. A device of the class described, comprising the combination of a sliding latch bolt, normally spring pressed outwardly; a pivoted lever for retracting said latch bolt, provided with an arm extending at right angles thereto at its upper end, and having 10 an eye therein; a roll-back having an arm extending downwardly and provided with a curved lower end disposed in said eye; and means for operating said roll-back.

3. A device of the class described comprising the combination of a sliding latch bolt, normally spring-pressed outwardly, a pivoted lever for retracting said latch bolt, provided with a lateral projection having a

recess formed therein, a roll-back having an arm engaging said lateral projection within 20 said recess and means for operating said roll-back.

4. A device of the class described comprising the combination of a sliding latch bolt, a spring for pressing the same outwardly, a 25 pivoted lever for actuating said latch bolt provided with a lateral projection having a recess formed therein, a roll-back having an arm engaging said lateral projection within said recess and a spring tending to move 30 said arm in an opposite direction to that in which the lever is actuated by the first mentioned spring.

In witness whereof I affix my signature.

THOMAS J. KEHOE.
